CLAIM

I claim the ornamental design for a desk organizer, as shown and described.

DESCRIPTION

FIG. 1 is a top, front, right perspective view of a desk organizer embodying the design;

FIG. 2 is a front elevational view of the desk organizer;

FIG. 3 is a rear elevational view of the desk organizer;

FIG. 4 is a top plan view of the desk organizer;

FIG. 5 is a bottom plan view of the desk organizer; and,

FIG. 6 is a left elevational view of the desk organizer, with the right side being a mirror image thereof.
